United States Patent Office

Des. 229,035
Patented Nov. 6, 1973

229,035

FUEL CAN

Paul F. Quick, Hartford, Wis., assignor to Chrysler
Corporation, Highland Park, Mich.

Filed July 29, 1971, Ser. No. 167,545

Term of patent 14 years

Int. Cl. D9—02

U.S. Cl. D9—175

FIG. 1.

FIG. 1 is a front elevational view of a fuel can embodying my new design;

FIG. 2 is a top plan view;

FIG. 3 is a side elevational view; and

FIG. 4 is a rear elevational view.

I claim:

The ornamental design for a fuel can, substantially as shown.
